United States Patent Office

Des. 228,137
Patented Aug. 14, 1973

228,137

DATA ENTRY UNIT

George E. Chadima, Jr., 3624 Skylark Lane SE.,
Cedar Rapids, Iowa 52403

Filed Feb. 4, 1971, Ser. No. 112,837

Term of patent 14 years

Int. Cl. D14—02

U.S. Cl. D26—5 C

FIG. 1 is a front perspective view of a data entry unit showing my new design.

FIG. 2 is a side view of the unit shown in FIG. 1. The opposite side view is in all material respects the same as that shown in FIG. 2.

FIG. 3 is a front view of the unit shown in FIG. 1. The rear view is the same as the front view in all material respects.

I claim:

The ornamental design for a data entry unit, substantially as shown and described.
